UNITED STATES PATENT OFFICE.

CHARLES E. LUCKE, OF NEW YORK, N. Y., ASSIGNOR, BY DIRECT AND MESNE ASSIGNMENTS, OF ONE-THIRD TO LOUIS WILPUTTE AND TWO-THIRDS TO ALICE A. WILPUTTE, BOTH OF NEW ROCHELLE, NEW YORK.

COKE-OVEN.

1,371,315.

Specification of Letters Patent. Patented Mar. 15, 1921.

Application filed August 30, 1917, Serial No. 183,913. Renewed August 13, 1920. Serial No. 403,300.

To all whom it may concern:

Be it known that I, CHARLES E. LUCKE, a citizen of the United States of America, residing in the city, county, and State of New York, have invented certain new and useful Improvements in Coke-Ovens, of which the following is a true and exact description, reference being had to the accompanying drawings, which form a part thereof.

My present invention relates to regenerative coke ovens and particularly to regenerative coke ovens of the type disclosed in the prior Patent, No. 1,212,866, granted January 16, 1917 to Louis Wilputte, and consists in a novel arrangement of the outlet connections from the regenerative chambers, devised with the general object of entirely segregating the waste gas outlets from the different regenerators and thereby obtaining a more perfect control of the distribution of flow among the various oven heating flues.

The various features of novelty which characterize my invention are pointed out with particularity in the claims annexed hereto and forming a part of this specification. For a better understanding of the invention, however, and of the advantages possessed by it, reference should be had to the accompanying drawings and descriptive matter, in which I have illustrated and described various forms of apparatus embodying the invention and by which each may be carried out.

Of the drawings:

Figure 1 is a sectional elevation of a coke oven, the section being taken on the line 1—1 of Fig. 3;

40 Fig. 2 is a section on the line 2—2 of Fig. 1, and

Fig. 3 is a section taken partly on the line 3—3 and partly on the line 3A—3A of Fig. 1.

45 In the drawings A represents parallel, horizontally elongated coking chambers formed in the coke oven structure. The walls separating the chambers A are made hollow, as usual, to provide heating chambers which are divided up into a series of vertical heating flues B by the partitions C and CC, and open at their upper ends into the usual common horizontal flues D. E represents slide dampers mounted on the tops

of the partition C employed to regulate the port area by which each flue B is connected at its upper end to the corresponding common horizontal flue D. Channels F running from the flues D to the top of the oven structure are provided as usual to permit the adjustment of the slides E, as well as of the gas burner nozzles hereinafter referred to. The passages F are normally closed at their upper ends. In the lower portion of the coke oven structure are located alternately arranged regenerator chambers G and GA, which run transversely to the length of the heating chambers and are separated from one another by the transverse partition walls H. In order to obtain the desired structural strength, wall portions I extend across the regenerative spaces between the division walls H and beneath the heating wall between the chambers A. Large ports or passages I' are formed in the wall portions I, however, so that the latter do not interfere with the practical continuity of the transversely running regenerative chambers. The checker brick is advantageously disposed in the passages I' as well as in the spaces between the walls I. Each flue B is connected at the bottom, in the particular form shown in the drawings, with one regenerative chamber G and with one regenerative chamber GA, by a corresponding pair of passages g, and each of the regenerative chambers G and GA is connected by two passages g to two different flues B for a reason hereinafter explained. Gas burner pipes J are located in passages formed in the oven structure beneath the flues B and supply gas through the ported nipples J' and burner nozzles K into burner chambers K' opening one into the bottom of each flue B.

40 The supply connection to the regenerative chambers G and GA comprise a series of alternately arranged pipes M and MA at each side of the battery. Each of the pipes M and MA is located in a corresponding passage L formed in the lower portion of the masonry structure and, as shown, in line with the portions I. Each of the pipes M and MA are formed with suitably proportioned and arranged discharge orifices M'. The orifices M' of each pipe M register with a corresponding set of vertical passages L' opening from the corresponding passage L into the regenerative chambers G above,

while the discharge orifices M' of each pipe MA register with another set of vertical passages L' opening from the corresponding passage L into the regenerative chambers 5 GA above, as is shown clearly in Fig. 2.

The burner pipes J are arranged in aligned pairs extending into the oven structure or battery from its opposite sides, and the same is true of the supply pipes M and the supply 10 pipes MA. The pipes M and MA are preferably removably mounted in place so that they may be withdrawn for cleaning, removal, or to permit the orifices M' to be adjusted, which may easily be done in some 15 cases by reaming out the orifices and in other cases by replacing the withdrawn pipe by a new one in which the orifices are of the proper size.

Each of the supply pipes M and MA at 20 one side of the oven structure is connected to the corresponding one of a pair of tunnels or flues Q running along the opposite sides of the battery. In the connection shown each of the pipes M is connected to the 25 corresponding flue Q by a simple elbow and pipe section M^{10} , and each of the pipes MA is connected to the corresponding flue Q by a pipe connection M^{11} , including a cutoff valve M^{12} . In addition each of the pipes 30 MA is connected to the corresponding one of a pair of gas supply mains R by a pipe connection M^{13} , including a reversing valve M^{14} , having an operating arm M^{15} . Each 35 burner pipe J is also connected to the corresponding gas main R by a pipe connection J^{10} including a cutoff valve J^{11} and a reversing valve J^{12} . Each reversing valve J^{12} is provided with an operating arm J^{13} and the various operating arms J^{13} and M^{15} 40 are in practice connected to a suitable reversing mechanism.

The regenerative chambers G and GA are connected by a series of ports P formed in 45 the bottom walls of these chambers each to a corresponding one of a series of waste gas sole channels N. The channels N extend transversely to the oven chamber A and in the preferred construction illustrated each lies immediately beneath the regenerator 50 chamber G or GA to which it is connected by the corresponding ports P.

Each of the sole channels N is connected through an undivided valve casing U to an offtake flue QA, which runs along one end 55 of the battery and leads to a suitable stack (not shown). Each valve casing U is provided with an adjustable throttling damper U' and with a cutoff valve U² which may be moved toward and away from its seat by a 60 corresponding valve operating arm U³, connected to reversing mechanism which may be of the usual character.

The particular oven construction described 65 is adapted for operation in two different ways. In one contemplated mode of opera-

tion the oven is commonly described as operating as a "coke oven", and in this case the combustible gas supplied for heating the oven is gas generated in the chambers A, which after being purified and cooled is 70 supplied to the appropriate burner pipes J through the corresponding one of the two gas mains R. In this case the valves M^{12} in the pipe connections M^{11} are all open, the reversing valves M^{14} in the pipe connections 75 M^{13} are all closed, and the regenerative chambers G and GA are all employed to preheat air supplied to the lower ends of the flues B. During each period of operation as a "coke oven" in which combustion 80 begins, for example, in the flues B at the left hand side of the battery as seen in Fig. 3 the left hand flue Q is supplied with air preferably under pressure slightly above that of the atmosphere and passes the air 85 thus received to all of the regenerative spaces G and GA under the left hand side of the oven through the pipe connections M^{10} and M^{11} , and the supply pipes M and MA. At the same time all of the gas valves 90 J^{12} at the left hand side of the battery are open and combustible gas is supplied to the corresponding burner pipes J through the left hand gas main R from the coke oven gas supply connection. The air supply to 95 the flue Q at the right hand side of the battery is at this time cut off. In this condition of operation the valves disks U^2 in all the valve casings U connected to the sole channels N under the left hand side of the battery are seated, while all the valve disks U^2 100 in the valve casings U connected to the sole channels under the right hand side of the battery are open. Operating in this manner the air supporting combustion is preheated 105 as it passes up at the left hand side of the oven to the flues B in which combustion is to begin, while the burnt gases descend through all of the regenerative chambers under the right hand side of the oven and 110 heat up the checker work in the latter. After operating with this direction of flow for the prescribed period, which is usually about thirty minutes, the direction of flow through the various regenerative spaces and 115 heating flues is reversed by closing the gas valves J^{12} at the left hand side of the battery, and opening the corresponding valves J^{12} at the right hand side of the battery, opening the valves U^2 at the left hand side 120 of the battery and closing the valves U^2 at the right hand side of the battery, and disconnecting the left hand flue Q from the source of air supply while connecting to the latter the right hand flue Q.

In the second contemplated mode of operation the oven is commonly said to operate as a "gas oven," and in this case the combustible gas supplied for heating the oven is producer or like gas, which is preheated be- 130

fore passing to the combustion flues B by being passed through the regenerative chambers GA. In this case the valves in the pipe connections J¹⁰ are adjusted to close said 5 connections, the reversing valves M¹⁴ in the pipe connections M¹³ at one side of the battery are open, and the valves M¹⁴ at the other side of the battery are closed, the stop valves M¹² in the pipe connection M¹¹ are all closed, 10 and the mains R are connected to the producer or like gas supply system. When the oven is operated as a "gas oven" with combustion starting in the flues B at the left hand side of the battery, air is supplied to 15 the left hand regenerative chambers G through the pipes M from the corresponding flue Q as when the oven is operating as a "coke oven." At the same time combustible gas passes from the left hand gas main R 20 through the corresponding valves M¹⁴, which are then open, the left hand pipes MA and thence to the left hand regenerator chambers GA and is preheated in the latter. In this mode and stage of operation, the 25 burnt gases descend through and reheat the regenerator chambers G and GA under the right end half of the oven structure. The right hand valves U² being then closed and the left hand valves U² being then open. 30 When the direction of the flow through the combustion flues is reversed the previously open valves M¹⁴ and U² are closed, and the previously closed valves M¹⁴ and U² are 35 opened, the right-hand flue Q is disconnected from the source of air supply and the left hand flue is connected thereto.

With the apparatus described it is possible by suitably proportioning the discharge ports M' of the supply pipes M and M' to 40 supply exactly the proper amount of air to the different regenerators G, and air or gas, depending upon whether the oven is used as a "coke oven" or "gas oven," to the regenerative chambers GA. 45 The various outlet ports P, and the sole channels N should ordinarily be initially or relatively so proportioned that the flow into each sole channel N from the regenerator chamber above it through the corresponding 50 ports P is uniformly distributed among the latter. When each of the sole channels taper in cross section, as indicated in the drawings, so that the velocity of flow through the sole channel is the same at all points along the 55 length of the latter the corresponding ports P should all be of the same size. The distribution of flow through the different sole channels N, and consequently the distribution of downward flow among the different 60 flues B in each heating wall may be regulated by the setting of the various throttling dampers U'.

The provisions described for accurately proportioning the supply of the air or air 65 and gas to be preheated in the different re-

generators, and for adjusting the supply of combustible gas supplied to the various flues B from the burner pipes J made possible by the use of removable burner nozzles J', coupled with the adjustable slide chambers E, 70 and a proper initial proportioning of the various waste gas outlets and sole channels connected to the different regenerator chambers, make it possible to obtain the distribution of both the ascending and descending 75 streams of burning gas in the combustion flue B and regenerators necessary to insure the desired uniform coking of the coal charged into the chambers A.

The provision of separate sole channels 80 for the regenerative spaces connected to the different flues B not only prevents any possibility of a flow from one regenerator space to another through the sole channels with a consequent disturbance of the distribution of 85 upward flow through the flues but also permits a regulation of the distribution of downward flow by adjusting the throttle damper U'.

While in accordance with the provisions 90 of the statutes I have illustrated the best form of my invention now known to me, it will be apparent to those skilled in the art that many changes may be made in the form of the apparatus disclosed without departing 95 from the spirit of my invention, and that certain features of invention disclosed herein may sometimes be used with advantage without a corresponding use of other features.

Having now described my invention, what 100 I claim as new and desire to secure by Letters Patent, is:

1. In a regenerative coke oven having a coking chamber, a heating wall at the side 105 of said chamber, two groups of heating flues in said heating wall, and a passage to which one end of each of the flues in both groups is connected, a set of regenerators to which the opposite ends of the flues in one group 110 are connected, and another set of regenerators to which the opposite ends of the flues in the other group are connected, each regenerator being connected to a part only of the flues in the group to which the corresponding set of regenerators is connected, and supply connection to the various regenerators, the improvements consisting in individual valved waste gas outlet connections 115 to the various regenerators. 120

2. In a regenerative coke oven having parallel horizontal coking chambers, heating walls between said chambers, two groups of heating flues and an upper horizontal passage to which the upper end of each of the 125 flues in both groups is connected in each heating wall, a set of regenerators running transversely to, and beneath the chambers and heating walls, to which the lower ends of the flues in one group of each of the 130

various heating walls are connected, and another set of similarly located regenerators to which the lower ends of the remaining flues are connected, each regenerator being 5 connected to a part only of the flues in the group of each heating wall to which the corresponding set of regenerators is connected, and supply means for the various regenerators, the improvement which 10 consists in individual waste gas sole channels for the different regenerators.

3. In a regenerative coke oven having parallel horizontal coking chambers, heating walls between said chambers, two groups of 15 heating flues and an upper horizontal passage to which the upper end of each of the flues in both groups is connected in each heating wall, a set of regenerators running transversely to, and beneath the chambers 20 and heating walls to which the lower ends of the flues in one group of each of the various heating walls are connected, and another set of similarly located regenerators to which the lower ends of the remaining flues are 25 connected, each regenerator being connected to a part only of the flues in the group of each heating wall to which the corresponding set of regenerators is connected, and supply means for the various regenerators, 30 the improvement which consists in a separate waste gas outlet channel for each regenerator running along the latter and communicating therewith at distributed points along the length of the regenerator.

35 4. In a regenerative coke oven having parallel horizontal coking chambers, heating walls between said chambers, two groups of heating flues and an upper horizontal passage to which the upper end of each of the 40 flues in both groups is connected in each heating wall, a set of regenerators running

transversely to, and beneath the chambers and heating walls to which the lower ends of the flues in one group of each of the various heating walls are connected, and another set of similarly located regenerators to which the lower ends of the remaining flues are connected, each regenerator being 45 connected to a part only of the flues in the group of each heating wall to which the corresponding set of regenerators is connected, and supply means for the various regenerators, the improvement which 50 consists in a separate gas outlet channel for each regenerator running along the under 55 side of the latter, and valves controlling the flow out of said channels.

5. In a regenerative coke oven having parallel horizontal coking chambers, heating walls between said chambers, two groups of 60 heating flues and an upper horizontal passage to which the upper end of each of the flues in both groups is connected in each heating wall, a set of regenerators running transversely to, and beneath the chambers 65 and heating walls to which the lower ends of the flues in one group of each of the various heating walls are connected, and another set of similarly located regenerators to which the lower ends of the remaining flues are 70 connected, each regenerator being connected to a part only of the flues in the group of each heating wall to which the corresponding set of regenerators is connected, and supply means for the various regenerators, the 75 improvement which consists in separate waste gas outlet channels for the various regenerators running parallel to the regenerators, and a common stack flue to which said channels are individually connected at the 80 end of the oven.

CHARLES E. LUCKE.
